Primary Examiner — Michael A Maharajh(74) *Attorney, Agent, or Firm* — Banner & Witcoff, Ltd.(57) **CLAIM**

The ornamental design for a wall mount for exercise rack, as shown and described.

DESCRIPTION

FIG. 1 is a top, front, right perspective view of a wall mount for exercise rack showing my new design; FIG. 2 is a top, front, left perspective view thereof; FIG. 3 is a top view thereof; FIG. 4 is a bottom view thereof; FIG. 5 is a right side view thereof; FIG. 6 is a left side view thereof; FIG. 7 is a front view thereof; and, FIG. 8 is a bottom, front, right perspective view thereof. The uneven-length broken lines immediately adjacent to the shaded area define the bounds of the claimed design and form no part thereof. The even-length broken lines depicting the remainder of the wall mount for exercise rack show features that form no part of the claimed design.
